DIVISION-WALL FOR WATER-TUBE BOILERS.

1,105,213.

Specification of Letters Patent. Patented July 28, 1914.

Application filed September 10, 1912. Serial No. 719,512.

To all whom it may concern:

Be it known that we, WILLIAM F. SELLERS and HENRY B. BRADFORD, citizens of the United States, residing in Edgemoor, 5 Brandywine Hundred, county of Newcastle, and State of Delaware, have invented a certain new and useful Improvement in Division-Walls for Water-Tube Boilers, of which the following is a true and exact description, reference being had to the accompanying drawings, which form a part thereof.

Our present invention relates to water tube boilers and particularly to the construction of the baffle or division walls employed to divide the space between the water tubes into separate passes for the hot products of combustion from the furnace of the boiler.

The object of the invention is to provide 20 a simple and durable division wall construction which may be installed with comparative ease and at a relatively low cost.

The various features of novelty which characterize our invention are pointed out 25 with particularity in the claims annexed to and forming a part of this specification. For a better understanding of the invention, however, and of the advantages possessed by it, reference should be had to the accompanying drawings and descriptive matter 30 which I have illustrated, and described in detailed forms in which the invention may be embodied.

Of the drawings: Figure 1 is a longitudinal sectional elevation of a water tube boiler of familiar type, equipped with division walls embodying a preferred form of our invention. Fig. 2 is a partial sectional elevation taken on the line 2—2 of Fig. 1, but 35 on a larger scale, with parts of the division wall broken away and removed to facilitate an understanding of the division wall construction. Fig. 3 is a sectional elevation taken on the line 3—3 of Fig. 2, but on a 40 still larger scale.

In the drawings, A and B represent the front and rear headers of a water tube boiler. These headers are connected by a 45 bank of water tubes C which are slightly inclined to the horizontal. Above the bank

of water tubes C are located the steam and water drum or drums D which connect the upper ends of the headers.

E, E, represent the end walls of the boiler housing, and F, F, represent the side walls 55 of the boiler housing.

G represents the bridge wall located beneath the water tubes at the rear end of the furnace chamber, and H and I represent the baffle or division walls employed to cause 60 the gaseous products of combustion, issuing from the furnace chamber, to pass upward through the intertube space adjacent the front header A, then downward through an intermediate portion of the intertube space, 65 and upward through the portion of the intertube space adjacent the rear header. In so far as above described the boiler construction is of a type which is well-known and in general use.

The division wall H, which rises from the bridge wall G, comprises, in the preferred construction illustrated, a skeleton frame work which is incorporated in and reinforces a body of suitable refractory material 75 which may advantageously be that commercially known as "hot blast cement" and which includes an asbestos fiber binder. This cement is highly refractory, and durable, and with the asbestos fiber binder incorporated in it, possesses considerable 80 mechanical strength.

As shown best in Figs. 2 and 3, the skeleton frame work of the division wall H comprises a parallel series of wrought metal 85 angle bars J, which are parallel to each other, and are inclined to the horizontal to correspond to the arrangement of water tubes C, which are so disposed that appreciable spaces exist between inclined rows of 90 the water tubes, whereas no such spaces exist between horizontal and vertical rows of the tubes. This arrangement of the water tubes is one commonly employed in certain types of water tube boilers. The skeleton 95 frame work also comprises a second set of wrought metal bars JA, which are parallel to each other, and lie between the rows of tube C which extend transversely to, though, as shown, not exactly perpendicular to the rows 100

of tubes between which the bars J are located. The angle bars J and JA are arranged so that their flanges J' extend transversely to the tubes C and abut against each other, while the flanges J² of the bars J and JA, extend toward the front and rear headers respectively of the boiler. The bars J and JA are connected together at appropriate points as by rivets or bolts J³. The 10 ends of the bars J and JA adjacent the side walls, F, F, of the housing are secured to vertical bars J⁴. To more effectually protect the lower ends of the wrought metal bars J and JA from the high temperatures 15 prevailing in the lower portions of the first pass for the hot gaseous products, cast metal sections K are employed. One of these sections is inserted between each pair of inclined rows of tubes C between which is also 20 located a corresponding angle bar JA. Each section K is notched at its opposite edges to receive the corresponding water tubes and may be inserted after the tubes C are put in place by first passing it between 25 the tubes with the plane of the section parallel to the length of the tubes, and then giving it a quarter turn about its longitudinal axis. Each adjacent pair of sections K meet in the spaces between the tubes of the 30 row engaged in part by each section. The cast iron sections may be connected together at various points by means of bolts or pins K'. The division wall I may be substantially identical in construction with the division wall H, except that, the cast metal sections K, are unnecessary and are omitted in the case of the wall I.

As shown in the drawings metallic soot cleaning pipes N and nozzles O and O' are 40 also incorporated in the divisions H and I. This arrangement of the soot cleaning apparatus forms no part of our joint invention, but is the sole invention of one of us, namely, Henry B. Bradford, and is disclosed 45 and claimed in his application for patent Serial No. 719,515 filed concurrently herewith. It is to be understood, of course, that our division wall construction does not necessarily involve the presence or use of tube 50 cleaning apparatus but it is one of the advantages of our invention that our division wall construction permits cleaning pipes and nozzles to be readily incorporated in it as shown herein and in more detail in said 55 application Serial No. 719,515.

The division walls H and I may be readily and comparatively inexpensively installed and are highly durable. In installing the division walls, the iron parts to be 60 incorporated in the cement body portion are first put in place and then the cement material is applied in a plastic condition. The plastic material thus plastered in place on the bars J and JA is supported by these

bars and the water tubes of the boiler, and 65 in turn serves to secure the bars and tubes together, thus anchoring the division wall in place.

While in accordance with the provisions of the statutes, we have illustrated and described the best forms of our invention now known to us it will be apparent to those skilled in the art that changes may be made in the form of the apparatus disclosed without departing from the spirit of our invention, and that under some conditions certain features of our invention may be used 75 to advantage without a corresponding use of other features.

Having now described our invention what 80 we claim as new and desire to secure by Letters Patent, is:

1. In a water tube boiler the combination with a bank of water tubes, of a transverse division wall which divides the intertube 85 space into separate passes for the hot gases, and comprising a skeleton framework formed of metallic bars passing through the spaces between the tubes transversely to the latter, some of said bars extending transversely to others, and a body portion of refractory material plastered on said bars and supported by and securing together said bars and said tubes.

2. In a water tube boiler, the combination 95 with a bank of substantially parallel water tubes arranged in transverse rows, of a division wall dividing the intertube space into separate passes for the hot gases, and comprising a body portion of refractory material 100 and a reinforcing skeleton framework incorporated therein, and comprising two transverse groups of metal bars arranged between the transverse rows of tubes, and means for securing the bars of one group to 105 bars of the other group, said means being adapted to secure the bars thereby connected after the said bars have been separately inserted in place between the said water tubes.

3. In a water tube boiler, the combination 110 with a bank of substantially parallel water tubes arranged in transverse rows, of a division wall dividing the intertube space into separate passes for the hot gases and comprising a body portion of refractory material 115 and a skeleton framework incorporated therein and comprising two transverse rows of wrought metal bars arranged between the transverse rows of tubes, and cast metal sections, also incorporated in said body portion 120 adjacent one edge of the wall and at one side of said wrought metal bars.

4. In a water tube boiler, the combination with a bank of substantially parallel water tubes arranged in transverse rows of a division wall dividing the intertube space into separate passes for the hot gases, and comprising a body portion of refractory ma- 125

terial and a reinforcing skeleton framework incorporated therein, and comprising two transverse groups of flanged metal bars arranged between the transverse rows of tubes and each having a flange transverse to, and flange parallel to the length of the water tubes, the transverse flanges of bars crossing

one another abutting against each other and being secured together.

WILLIAM F. SELLERS.
HENRY B. BRADFORD.
